UNITED STATES PATENT OFFICE.

DAVID BAKER, OF PHILADELPHIA, PENNSYLVANIA, ASSIGNOR TO LADD & BAKER, INCORPORATED, A CORPORATION OF PENNSYLVANIA.

ROTARY FURNACE.

968,313.

Specification of Letters Patent. Patented Aug. 23, 1910.

Application filed March 23, 1908, Serial No. 422,730. Renewed July 8, 1910. Serial No. 571,087.

To all whom it may concern:

Be it known that I, DAVID BAKER, of Philadelphia, county of Philadelphia, and State of Pennsylvania, have invented a new 5 and useful Improvement in Rotary Furnaces, of which the following is a specification.

This invention relates to furnaces for roasting or similarly treating materials, 10 such as ores, and is designed for the utilization of the sulfur contained in sulfurous ores, and also for the removal of the sulfur from those ores where the roasting process is the most difficult one, for example, zinc 15 blonde, and sulfid and sulfates carrying lead.

The invention relates to improvements in the type of furnace in which the furnace or kiln proper consists of a cylindrical shell supported at a slight inclination downward 20 and rotated on a longitudinal axis, the material to be treated being fed into the upper end of the cylinder and discharged from its lower end, and being subjected in its passage therethrough to an agitating or rolling action due to the rotation of the cylinder, and 25 being subjected also to the influence of a hot blast introduced into the discharge end of the cylinder.

In accordance with the present invention, 30 the rotary shell or furnace proper is formed with a central longitudinal roasting chamber supplied with a hot blast or flame, and a surrounding heating chamber separate from the roasting chamber and consisting of 35 a number of longitudinally extending heating flues, through which, burning gases are passed during the rotation of the cylinder, the result being that the contents of the roasting chamber may be kept entirely sep- 40 arate from the gases passing through the heating chamber. By this means, I am enabled to recover and utilize the sulfur contained in sulfurous ores. I am enabled also, by reason of the greater degree of heat to 45 which the roasting chamber may be subjected by the surrounding heating chamber, to remove the sulfur from such ores as zinc blonde and sulfids and sulfates carrying lead. I am also enabled in roasting fine ores, to 50 nodulize the same for subsequent use in the blast furnace, the nodulizing effects being secured by raising the temperature in the heating chamber and correspondingly in-

creasing the temperature in the roasting chamber, to form the material therein into 55 a pasty mass, which by the motion of the furnace is formed into balls as usual.

I prefer to employ in connection with a furnace of this construction, regenerative chambers to heat the blast supplied to the 60 roasting chamber, which regenerative chambers may by the adjustment of suitable valves be connected alternately with the heating flues and with a cold blast supply; whereby the burning gases after their 65 passage through the heating flues are utilized to heat the incoming blast for the roasting chamber.

The invention consists also in the details of construction and combination of parts 70 hereinafter described and claimed.

In the accompanying drawings:—Figure 1 is a side elevation of a furnace constructed in accordance with my invention. Fig. 2 is a longitudinal vertical section through the 75 same from end to end. Fig. 3 is a view of the rotary cylinder showing the same partly in end elevation and partly in transverse section. Fig. 4 is a transverse sectional elevation on the line 4—4 of Fig. 3. Fig. 5 80 is an end elevation of the rear or lower end of the rotating cylinder showing the nozzles through which the fuel gas is introduced into the combustion chamber, and thence into the heating flues. Fig. 6 is a diagrammatic view showing the circulation through the regenerative chambers of the incoming blast for the roasting chamber and the burning gases from the heating flues. 85

Referring to the drawings:—1 represents 90 a shell or cylinder constituting the furnace or kiln proper which extends at a slight inclination downward from the horizontal and which is rotatably supported on rollers 2, a rotary motion being imparted to the cylinder by any suitable mechanism, preferably by means of a drive shaft 3 provided with a driving pinion 4 meshing with a circular rack 5 on the exterior of the cylinder. 95

At its upper end the interior of the cylinder communicates with a fixed pipe or chamber 6 extending vertically and constituting a gas outlet through which the gaseous products from the combustion in the roasting chamber escape, the ore to be 100 roasted being introduced into the cylinder 105

by means of a downwardly inclined chute 7, extending diagonally through the end of the chamber 6 from the outside and having its inner end terminating within the receiving 5 end of the cylinder.

At its opposite end the interior of the cylinder communicates with and is closed by a header 8 terminating at its bottom in a hopper 9, in which the residuum from the 10 interior of the rotary cylinder is received and from which it may be discharged into cars traveling on a track beneath the hopper.

The cylinder 1 is formed with a central longitudinal passage 10, extending there- 15 through from end to end, and constituting a roasting chamber, and a number of longitudinally extending surrounding passages 11, constituting heating flues, which flues are separated from each other by radial par- 20 titions 11^a, and are separated from the roasting chamber by the outer wall 10^a of the latter, the roasting chamber and heating flues being thus separate from and inde- 25 pendent of each other, for a purpose to be presently described.

In order to resist the effects of the intense heat to which the walls of the flues and roasting chamber will be subjected, I propose to form the central chamber, the 30 radial partitions and outer walls of the flues of firebrick slabs, the whole being inclosed in a sheet metal sheathing.

At the discharge end of the cylinder, the heating flues communicate with an annular 35 enlarged chamber 12 surrounding the roasting chamber and constituting a combustion chamber, into which is introduced a mixture of fuel-gas and air, which mixture burning in the combustion chamber enters 40 the lower ends of the longitudinal heating flues and passing therethrough, find an exit at the opposite ends of the flues, as will be presently described.

In order that the introduction of the fuel 45 gas may take place while the cylinder is rotating, the rear wall of the combustion chamber 12 has formed therein two series of longitudinally extending alining nozzles 13 and 14, forming passageways through 50 said wall, the adjacent ends of the two series of nozzles being separated from each other a slight distance so as to form passages for the entrance of air from air openings 15 into the streams of gas flowing through said nozzles, which gas enters the outer series of 55 nozzles 14 through an annular slit 16 in the front wall of a fixed annular gas chamber 17 formed in the fixed header 8 and supplied with gas by means of a supply pipe leading 60 from any suitable source.

The adjacent walls of the fixed annular 55 gas chamber and the combustion chamber are flat and smooth so as to form when in contact a tight and close joint between the fixed and rotary parts, and in order that

this contact may be maintained, and the leakage of gas prevented, I propose to so sustain the header 8 that it will be capable of a movement longitudinally to and from the rotating cylinder, and I propose to subject the header to a constant pressure tending to hold it closely up against said cylinder. As shown in Figs. 1 and 3, this is accomplished by providing longitudinal tracks 18 at the discharge end of the cylinder, on 70 which travel wheels 19, journaled on the sides of the header 8, whereby the header is movable on said tracks to and from the end of the cylinder. The header 8 has attached to it on opposite sides ropes or cables 20 80 which pass over pulleys 21 mounted on fixed beams 22, to the end of which cables weights 23 are attached and tend to hold the header closely but yieldingly up against the end of the cylinder.

At the opposite end of the cylinder, the roasting chamber is extended longitudinally some distance beyond the ends of the heating flues in the form of a metallic neck 24, which has its end flanged and seated against 90 the flanged end of the gas outlet pipe 6, before alluded to, these two flanged surfaces being in close contact to form a tight joint. Both of these joints—that between the discharge end of the cylinder and the header 8, 95 and that between the receiving end of the cylinder and the gas outlet pipe 6—are kept cool by means of cooling pipes 25 and 26, the former being embedded in the flanged end of the gas outlet pipe, and the latter surrounding the slit through which the gas flows from the annular gas chamber into the nozzles.

The ends of the heating flues at the receiving end of the cylinder communicate 105 with an annular fixed chamber 27 formed with a front wall 28 and a rear wall 29, the front wall having an opening through which the neck 24 extends and is rotatably supported, and the rear wall being provided with an opening somewhat greater in diameter and in which the enlarged portion of the cylinder loosely fits, so that it will be free to rotate therein, as a result of which construction the burning gases flowing 110 through the heating flues will enter the said annular chamber 27.

The chamber 27 is connected by means of a flue 30 with two regenerative chambers 30 and 31, extending longitudinally beneath the rotary cylinder and having communication at their opposite ends, by means of branch flues 32 and 33, with a common flue 34 leading to a draft stack 36. A reversing valve 29^a controls the flow of the burning gases 120 from chamber 29 to the two regenerative chambers, while a reversing valve 37 controls the communication of the said chambers with the stack.

A blower or air-compressor 40 for supply- 130

ing the blast for the roasting chamber, communicates by means of a pipe 41 with two branch pipes 42 and 43, connected respectively with the two regenerative chambers, 5 the flow of the air from the blower to said chambers being controlled by a reversing valve 44. At their opposite ends, the two regenerative chambers communicate by means of branch pipes 45 and 46 with a 10 hot blast pipe 47, provided with a reversing valve 48 and connected by means of a sliding joint with a vertical pipe 49, extending horizontally through the rear wall of the header 8, in the form of a horizontal nozzle 50, terminating within the discharge end of the chamber 10, by means of which the hot blast is introduced into said chamber to promote the combustion of the materials therein. 15

20 By the proper manipulation of the several reversing valves 29^a, 37, 44 and 48, the heating gases from the heating flues may be caused to pass alternately through the regenerative chambers, thereby heating the fire brick, and to flow out through the stack; and the cold blast from the blower may be caused to pass alternately through the two regenerative chambers; whereby it will be heated, whence it will be caused to enter 25 the lower end of the roasting chamber.

In the operation of the furnace, the cylinder has imparted to it a rotary motion, and the ore or other material to be treated is fed by means of chute 7 into the receiving end 30 of the roasting chamber. The rotary motion of the cylinder and its downward inclination cause the ore to travel slowly toward the opposite end, while at the same time being rolled about and agitated, so that every portion 35 of it is subjected to the action of the hot blast which entering the discharge end of the roasting chamber traverses the latter and escapes with the liberated product gas through the gas outlet pipe 6 at the receiving end of the cylinder. During the roasting action to which the material is thus subjected, the roasting chamber is heated on the outside by means of the streams of 40 burning fuel gas flowing through heating flues 11, the gas entering said flues at the discharge end of the cylinder and leaving them at the opposite end, whence they pass back again toward the discharge end of the cylinder through one of the regenerative 45 chambers, and finally escape through the draft stack. At the same time, the cold blast from the blower flows through the other regenerative chamber, which had been 50 previously heated by the passage of the fuel gas therethrough, and the air in its passage becomes highly heated by the checker work in the chamber, and in this condition enters the roasting chamber through blast nozzle 50 as a hot blast. The roasted ore flows from 55 the discharge end of the roasting chamber

and is received in the hopper 9, from which it may be discharged from time to time into suitable receptacles.

It will be observed that the neck 24 of the roasting chamber, where it extends within 70 and through the annular fixed chamber 27, is thin, so that the heat from the roasting chamber at this point is radiated through the neck to the gases flowing through said chamber, and in this way an amount of heat 75 is saved, the loss of which would be a considerable item in the roasting or nodulizing of fine ores or residues. At the opposite end of the furnace, the radiation of the heat is from the combustion chamber to the roasting chamber, so that there is a regenerative 80 action of the heat of the combustion gases and the roasting chamber, the incoming hot combustion gases imparting its heat to the roasting chamber at one end, and the burning sulfur in the roasting chamber at the other end imparting its heat to the combustion gases.

Having thus described my invention, what I claim is:—

1. In a furnace of the type described, a rotary cylindrical furnace proper formed with a longitudinally extending roasting chamber having an extension at one end and to receive the material to be treated and positioned to effect a gradual movement of such material toward the discharge end of such roasting chamber, a series of longitudinally extending heating flues for the circulation of a heating medium along the external wall of the roasting chamber and in a direction opposite to the movement of the material, a combustion chamber surrounding the extension of the roasting chamber and with which said flues communicate, and 95 a gas chamber at the opposite end of said cylinder and also with which the flues communicate.

2. In a furnace of the type described, the combination with a rotary cylinder formed 110 with a longitudinally extending roasting chamber and surrounding heating flues and with a hollow extension having its wall of thickness less than that of the wall of the roasting chamber, of means for circulating 115 a heating medium through said flues in one direction, a combustion chamber from which said heating medium is conveyed into said flues and beyond which the roasting chamber extends, and means for introducing the 120 material to be treated into the receiving end of the roasting chamber, said cylinder being disposed to direct the movement of the material therein in a direction opposite to that of the movement of the heating medium 125 through the flues.

3. In a furnace of the type described, the combination with a rotary cylinder formed with a longitudinally extending roasting chamber and surrounding heating flues and 130

1
with a hollow extension having its wall of thickness less than that of the wall of the roasting chamber, of means for circulating a heating medium through said flues in one direction, a combustion chamber from which said heating medium is conveyed into said flues and beyond which the roasting chamber extends, means for introducing the material to be treated into the receiving end of the roasting chamber, said cylinder being disposed to direct the movement of the material therein in a direction opposite to that of the movement of the heating medium through the flues, and means for introducing a hot blast into the opposite end of the roasting chamber and in the direction of movement of the heating medium through the flues.

4. In a furnace of the type described, the combination with a rotary cylindrical furnace-section formed with a longitudinal roasting chamber and with an extension having its wall of less thickness than that of the roasting chamber and with surrounding longitudinal heating flues, of an annular combustion chamber with which said flues communicate and from which chamber the burning gases are introduced into the flues, and an annular gas chamber housing the extension of the roasting chamber and from which heat radiates through said extension into the roasting chamber.

5. In a furnace of the type described, the combination with a rotary cylindrical furnace-section formed with a central longitudinal roasting chamber, surrounding longitudinally extending heating flues, and an annular combustion chamber communicating with said flues, of a fixed annular fuel-gas chamber communicating with the combustion chamber.

6. In a furnace of the type described, the combination with a rotary furnace-section formed with heating flues, an annular combustion chamber communicating with said flues, longitudinally extending nozzles in the wall of the combustion chamber for the introduction of fuel-gas, and a fixed annular gas chamber formed with an annular opening communicating with the nozzles.

7. In a furnace of the type described, the combination with a rotary furnace-section formed with heating flues, and an annular combustion chamber communicating with said flues, of gas entrance openings extending through the wall of the annular chamber and disposed circularly around the longitudinal axis thereof, a fixed annular gas chamber, and an opening through the wall of the chamber extending circularly around the longitudinal axis of the combustion chamber, and communicating with the gas entrance openings therein.

8. In a furnace of the type described, the combination of a rotary furnace-section pro-

vided with longitudinal heating flues, and an annular combustion chamber communicating therewith, a series of longitudinally extending gas entrance nozzles in the wall of the combustion chamber, and air openings in said wall associated with the gas nozzles.

9. In a furnace of the type described, the combination with a rotary cylindrical furnace-section formed with a central roasting chamber and surrounding heating flues, of a non-rotatable header closing the end of the roasting chamber and adapted to receive the material discharged therefrom, and an annular gas chamber formed in the header and communicating with the heating flues.

10. In a furnace of the type described, the combination with a rotary cylindrical furnace-section, of a non-rotatable header movable longitudinally to and from the furnace section, and means for maintaining the header yieldingly against the end of the rotary section.

11. In a furnace of the type described, the combination with a rotary furnace-section formed with a roasting chamber and heating flues, and an annular combustion chamber communicating with said flues, of a non-rotatable header closing the discharge end of the furnace-section and movable to and from the same, an annular gas chamber formed in the header and having a front flat wall adapted to coöperate with the rear wall of the combustion chamber to form a tight joint between the parts, said walls being formed with communicating openings; whereby the gas supplied to the gas chamber will enter the combustion chamber, and means acting on the header and serving to hold the same yieldingly up to the end of the furnace-section with said coöperating walls in contact.

12. In a furnace of the type described, the combination with the rotary cylindrical furnace-section formed with a longitudinal roasting chamber and longitudinally extending surrounding heating flues, of a fixed annular gas receiving chamber surrounding, and radiating its heat to the roasting chamber and with which the discharge ends of said flues communicate and a hot-blast member extending into the discharge end of the roasting chamber, whereby a hot-blast may be introduced into said chamber to promote combustion therein.

13. In a furnace of the type described, the combination with a rotary cylindrical furnace-section formed with a central tubular roasting chamber and surrounding longitudinally extending heating flues, the said tubular chamber being extended beyond the ends of the flues, of a fixed annular chamber formed in one wall with an opening through which the extension of the roasting chamber loosely passes, and having its other

wall formed to receive the ends of the heating flues and a hot-blast member extending into the discharge end of the roasting chamber, whereby a hot-blast may be introduced 5 into said chamber to promote combustion therein.

14. In a furnace of the type described, the combination with a rotary cylindrical furnace-section provided with a roasting chamber and surrounding longitudinally extending heating flues, of means at one end of the flues for supplying the same with fuel-gas, an annular chamber at the opposite end of the flues to receive the gas flowing therethrough, regenerative chambers communicating with said annular chamber, and a reversing valve for controlling said communication.

15. In a furnace of the type described, 20 the combination with a rotary cylindrical furnace-section provided with a roasting chamber and heating flues, of means at one end of the flues for supplying the same with fuel-gas, regenerative chambers in communication with the said flues at their opposite ends, a reversing valve controlling said communication, a draft stack communicating with the regenerative chambers, a reversing valve controlling said communication, 25 means for supplying air blast to said regenerative chambers, a reversing valve controlling the said supply, a hot-blast nozzle entering the discharge end of the roasting chamber, a communication between the 30 nozzle and the regenerative chambers, and a reversing valve for controlling said communication.

16. In a furnace of the type described, the combination with a downwardly inclined 40 rotary cylindrical furnace-section provided with a central roasting chamber, longitudinally extending surrounding heating flues, and an annular combustion cham-

ber at the discharge end of the cylinder communicating with the flues, a non-rotatable hood inclosing the discharge end of the roasting chamber and adapted to receive the residuum therefrom, an annular gas chamber formed in said hood, the said gas chamber and combustion chamber being 45 provided with communicating openings forming a connection between said chambers, means for supplying the annular chamber with fuel-gas, an annular fixed chamber at the opposite end of the cylinder communicating with the heating flues and adapted to receive the burning gases therefrom, a gas outlet at the receiving end of the roasting chamber, and means for introducing the material to be treated into the receiving 50 end of the roasting chamber.

17. In a furnace of the type described, a rotary cylindrical furnace proper formed with a longitudinally extending roasting chamber to receive the materials to be 55 treated and with surrounding heating flues for the circulation of a heating medium and whereby the contents of the roasting chamber are kept separate from the heating medium to facilitate the recovery and utilization of the product-gas liberated in the roasting chamber, said roasting chamber being extended beyond the heating flues and formed by a wall of thickness less than that of the roasting chamber, and a gas chamber 70 surrounding said extending portion of the roasting chamber and from which heat therein contained radiates through said extended portion into the roasting chamber.

In testimony whereof I hereunto set my 80 hand this tenth of March, 1908, in the presence of two attesting witnesses.

DAVID BAKER.
